WELL FLOW APPARATUS

Vestal A. Kagay, Dallas, Tex.

Application November 12, 1947, Serial No. 785,447

10 Claims. (Cl. 103—232)

1

This invention relates to new and useful improvements in well flow apparatus.

One object of the invention is to provide an improved apparatus for controlling the admission of a lifting fluid, such as gas, into a liquid column within a well tubing or conductor for lifting or raising the liquid to the surface, said apparatus being particularly adapted for use as an intermitter to intermittently admit the lifting gas at predetermined intervals in accordance with particular well conditions.

Various types of intermitter flow devices, such as are disclosed in the patents to Walton No. 2,385,316 and 2,391,605 and to Peters No. 2,342,301, employ a main valve which controls the admission of the lifting medium or gas into the well conductor, with the main valve being controlled in its operation by a pilot valve means. In this type of device, the pilot valve is usually actuated solely by the pressure of the lifting medium or gas whereby when the pressure of such medium reaches a predetermined point, the pilot is actuated to open the main valve. The main valve controls flow of the lifting medium into the well conductor through an inlet port or opening and obviously the size of the flow device and its various elements, such as its admission port, are restricted by the size of the well bore; in other words, the device cannot be increased in size beyond the physical limitation of the bore. Thus, the size or area of the admission port or opening of a flow device of this character has its limitations with the result that the volume of lifting gas which may be admitted upon opening of the main valve of the device is restricted, as determined by the area or size of said admission or inlet port. As wells are drilled to deeper depths, a greater volume of lifting gas is necessarily desirable upon each operation of the flow apparatus but because it is not practical to increase the size of the inlet port or other elements of the flow device beyond certain limits, the capacity of said device is insufficient. Attempts have been made to employ a series of intermitter flow devices but the difficulty of properly adjusting the devices to operate simultaneously has made their use an impractical solution to the problem.

It is one object of the present invention to provide an improved flow control apparatus which will admit a sufficient or desired volume of the lifting medium or gas into the well conductor upon each operation of the apparatus, whereby sufficient gas for lifting or raising the liquid column within said conductor is assured.

An important object of the invention is to pro-

vide an improved flow control apparatus, wherein two or more power or main valve units which control the admission of lifting fluid into a well conductor are actuated by a single pilot valve mechanism, whereby simultaneous operation of the main valve units is accomplished; more or less of said main valve units being employed in accordance with the particular volume of lifting fluid which is required to raise the well liquid within the conductor.

Still another object of the invention is to provide an improved well flow apparatus, wherein a plurality of main valve units are connected in the well conductor for controlling the admission of a lifting fluid into said conductor with each unit including a pressure-actuated main valve; said apparatus also having a single pilot valve unit for controlling the application of pressure to the pressure-actuated valves of the main valve units, whereby when said pilot is actuated, the main valve units are simultaneously operated as a single device to admit lifting fluid to the well conductor.

A further object of the invention is to provide an improved apparatus, of the character described, wherein a single pilot valve controls the operation of a plurality of main valve units and wherein said pilot valve is actuated solely in accordance with the pressure of the lifting fluid, whereby when said pressure reaches a predetermined point the main valve units are operated to admit said lifting into a well conductor.

A still further object of the invention is to provide an apparatus, of the character described, which is so constructed that any desired or required number of main valve units may be readily connected to the single pilot control valve unit, whereby the apparatus may be readily adapted to varying well conditions, which may occur in different production areas without any material change in the construction of said apparatus.

The construction designed to carry out the invention will be hereinafter described together with other features of the invention.

The invention will be more readily understood from a reading of the following specification and by reference to the accompanying drawing, wherein an example of the invention is shown, and wherein:

Figure 1 is an elevation of an apparatus, constructed in accordance with the invention, and illustrating the same mounted on a well conductor,

Figure 2 is an elevation of the apparatus taken at a right angle to the parts as shown in Figure 1,

Figure 3 is a transverse, vertical, sectional view

of the pilot valve and one of the main valve units. Figure 4 is an enlarged, horizontal, cross-sectional view, taken on the line 4—4 of Figure 3, and

Figure 5 is an enlarged, horizontal, cross-sectional view, taken on the line 5—5 of Figure 3.

In the drawings, the numeral 10 designates a well conductor or tubing which extends axially through the usual well casing 11. As is well known the well fluids enter the lower end of the tubing and flow upwardly therethrough, the annular space between the tubing and casing being packed off near its lower end by a suitable packer (not shown). The well liquids rise upwardly within the well tubing to a normal level in accordance with the particular well conditions and the improved well flow apparatus constructed in accordance with the present invention, is arranged to control the admission of a lifting fluid, such as gas or air, from the annular space outside of the tubing 10 and into said tubing. The admission of the lifting fluid will function to raise or lift the well liquids within the conductor or tubing to the surface in the usual manner.

The flow apparatus includes a pilot valve unit A which is coupled to the upper end of a main valve unit B. The valve unit B has communication through a port 12 with the well tubing and disposed below the unit B is a second main valve unit C which communicates with the tubing through an inlet port 13. Each of the units B and C, as will be explained, function to control the admission of the lifting fluid which is present in the annular space between the casing and the tubing, into the interior of the tubing and both of these units are controlled in their operation by the pilot valve unit A. Normally the main valve units B and C are in closed position with no flow occurring into the tubing 10. When the pressure within the annular space outside of the tubing 10 exceeds a predetermined amount, the pilot valve unit A is actuated to permit the application of pressure to the main valve unit B through a passage 14 which is mounted within a coupling 15 connecting the units A and B; pressure is also applied through a pressure line 16 to the lower main valve unit C. Thus, when the pilot valve unit A operates, pressure is directed to the units B and C to permit flow through the inlet ports 12 and 13. It will be evident that since both control units B and C are actuated by the pilot valve, actuation of said units will be simultaneous.

Although two main valve units are illustrated in the drawing, it is obvious that any desired number of such units may be mounted in series with all of said units being controlled by the single pilot valve unit A. The number of units B and C which are employed is dependent upon the volume of lifting fluid which is to be introduced into the tubing upon one operation for obviously a greater or lesser number of units will provide a greater or lesser number of ports with a resultant increase or decrease in inlet area. Additional main valve units may be operated by the single pilot by merely connecting additional pressure lines to the pressure line 16.

The particular type of pilot valve unit, as well as the particular construction of the main valve units is subject to some variation. So long as the units are adapted to be pressure-actuated, the purposes of the present invention may be accomplished. In Figures 3 to 5 one type of construction adaptable for the purpose is illustrated. As shown in these figures, the pilot valve unit A in-

cludes an outer cylindrical casing 20 which has its upper end closed by a suitable cap 21. An expandable bellows 22 has its upper end secured to a flanged collar 23 which is interposed between the upper end of the casing and the cap member. The lower end of the bellows is secured to the stem 24 of a pilot valve 25. The pilot valve is adapted to engage a valve seat 26 and is normally urged toward said seat by a coil spring 27 which has its lower end resting upon adjusting nuts 28 on the stem, with its upper end engaged beneath an internal flange 29 provided in the lower end of a protective sleeve 30a which surrounds the bellows 22. Normally the bellows tends to expand so that the force thereof, plus the force of the spring 27 urges the pilot valve 25 to a seated position.

A plurality of radial ports 30 extend through the wall of the casing 20 whereby the pressure of the lifting fluid in the annular space outside of the tubing may enter the interior of the casing 20 and act upon the bellows 22, such pressure tending to collapse the bellows. When the pressure of the lifting fluid acting upon the bellows reaches a predetermined point, sufficient to overcome the inherent resiliency of the bellows plus the pressure of the spring 27, the bellows is urged toward a collapsed position, whereby the pilot valve 25 is unseated to open the axial port 26a in the valve seat 26.

The valve seat is threaded into the coupling 15 which connects the casing 20 of the pilot valve unit A to the unit B and the axial opening 26a in said valve seat is in communication with the axial passage 14 of said coupling. Thus, when the pilot valve is unseated the pressure of the lifting fluid is admitted into the passage 14 of the coupling.

The main valve units B and C have been illustrated as comprising an outer housing which is formed of an upper tubular section 31 connected to a lower tubular section 32 by a coupling 33. Secured to the lower section 32 is a valve cage 34 having an inlet tube 35 threaded onto its lower end. A power bellows 36 has its lower end secured to an axial extension 33a formed on the coupling 33 while its upper end is fastened to a circular disk or head member 37. The head 37 is formed with a depending shank 38 which extends axially through the power bellows and which has its lower portion reduced as indicated at 39. This lower reduced portion is hexagonal in cross-section and extends through an axial bore 40, circular in cross-section, in the coupling 33. The extreme lower end of the reduced portion 39 of the shank 38 is adapted to engage the upper end of a fluted valve stem 41. The valve stem extends through a bore 42 within the upper end of the valve cage 34 and has a valve member 43 integral with its lower end, said member being adapted to engage a valve seat 44 provided within the cage. The upper end of the fluted valve stem 41 is movable within the tubular section 32 and the bore of said section has communication through a radial port 45 with the inlet port 12 of the tubing.

It will be evident that when the pilot valve 25 is open, the pressure of the lifting fluid is admitted to the upper end of the unit B and acts upon the power bellows 36. This power bellows is normally expanded which holds the shank 38 in a raised position, whereby the lifting fluid pressure acting through the inlet tube 35 and against the lower end of the main valve member 43 holds said main valve member seated. Admission of pres-

sure into the unit B permitting the same to act upon the bellows, causes said bellows to move toward a collapsed position, whereby the shank 38 is moved downwardly to move the main valve 43 downwardly off of its seat 44. It is noted that the cross-sectional area of the head 37 at the upper end of the power bellows 36 is greater than the effective area of the valve seat being acted upon by the lifting fluid pressure and this permits the valve to move downwardly to an unseated position. As soon as the main valve opens, the lifting fluid within the annular space may flow into the tubing through the inlet port 12.

The main valve unit C is constructed in an identical manner to the unit B with the exception that a cap or closure 46 is threaded into the upper tubular section 31 of the unit C in place of the coupling 15 which is secured in the upper end of the unit B. The cap 46 has the lower end of the pressure line 16 connected therein and a bore 47 in said cap permits the pressure from the line 16 to be applied to the power bellows 36 of the unit C. The upper end of the pressure line is connected into a radial port 48 which is formed in the coupling 15 and which communicates with the axial passage 14 thereof. It is, therefore, obvious that when the pilot valve 25 is unseated, the pressure of the lifting medium which is normally present in the annular space may flow downwardly to the power bellows 36 of both of the units B and C to simultaneously actuate said bellows and open the main valves 43 of said units. This admits the pressure of the lifting fluid into the tubing through the ports 12 and 13. It is pointed out that as a matter of convenience, the pilot valve unit A is shown as coupled to the upper main valve unit B through the coupling collar 15; however, it would be possible to make the pilot valve unit A entirely separate and connect the same to the unit B by means of a pressure line similar to the line 16. Also, it is within the scope of the present invention to employ more than two main valve units B and C since obviously any desired number may be connected by merely adding additional pressure lines which will extend from the line 16 to the various additional units. The operation of the apparatus is believed to be obvious from the foregoing.

Normally the main valves 43 of the units B and C are closed, as is the pilot valve 25. When the pressure of the lifting fluid within the annular space is raised to a predetermined amount, in accordance with the inherent pressure of the pilot bellows 22 plus the pressure of the spring 27, the pilot bellows 22 is actuated to unseat the pilot valve. When this occurs, the pressure of the lifting fluid within the annular space is simultaneously admitted to the power bellows 36 of both of the units B and C. As explained, this pressure acting upon the bellows of each unit will result in a downward movement of the valve members 43 of said units whereby the lifting fluid from the annular space may flow past the valves 43 and through the ports 12 and 13 into the tubing 10. The admitted lifting fluid will, of course, lift or raise the well liquids present in the well tubing to the surface. As soon as the pressure within the annular space falls below the amount for which the pilot valve unit A is adjusted, the pilot valve 25 is seated to shut off the application of pressure to the power bellows 36 of the main valve units B and C. Any pressure within the upper section 31 of the main valve units may escape through a relief orifice 49 which establishes communication

through the section 31 and the bore 40 of the coupling 33. As soon as pressure acting on the pilot bellows 36 is shut off, the pressure of the fluid acting against the valve 43 of each unit B and C will move the same to a closed position. The parts will remain in such position until the next operation, at which time the pilot valve 25 is again opened.

As has been noted, the particular construction 10 of the pilot valve unit A, as well as that of the main valve units B and C, is subject to variation. So long as these units are pressure-actuated, the improved results may be obtained. The 15 primary feature of the present invention is the use of two or more main valve units which control the admission of lifting fluid into the well casing, with said main valve units being controlled by a single pilot valve device. The use of the single pilot valve not only simplifies the construction but also assures that all of the main 20 valve units will be operated simultaneously to admit the lifting fluid. It will be evident that the use of a plurality of main valve units permits an increase in the volume of admitted lifting 25 fluid to take care of the particular well conditions which may be encountered.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

35. 1. A well flow apparatus including, a well conductor, a pair of main valve units connected with said conductor, each main valve unit having means for controlling the flow of pressure fluid which is present exteriorly of the conductor into said conductor, and a single pilot valve assembly forming part of one of said units and adapted to be actuated by the pressure exteriorly of the conductor, said pilot valve assembly being operatively connected to the main valve unit of which it forms a part, a pressure line extending from the pilot valve to the other main valve unit for controlling the operation of said second main valve unit, whereby a simultaneous operation of the main valve units is effected when the pilot 50 valve assembly is actuated.

2. A well flow apparatus including, a well conductor, a pair of main valve units connected with said conductor, each main valve unit having means for controlling the flow of pressure fluid which is present exteriorly of the conductor into said conductor, a single pilot valve assembly forming part of one of the main valve units and adapted to be actuated by the pressure exteriorly of the conductor, said pilot valve assembly being operatively connected to said unit, a pressure line extending from the pilot valve assembly to the other main valve unit for controlling the operation of said second main valve unit, whereby a simultaneous operation of the main valve units is effected when the pilot valve assembly is actuated, and means forming part of the pilot valve assembly and responsive to the pressure of the fluid exteriorly of the conductor for actuating the pilot valve when the pressure of said fluid reaches a predetermined point.

3. A well flow apparatus including, a well conductor which extends axially within a well bore, a pair of main valve units connected in said conductor, each unit having a flow passage establishing communication between the exterior and in-

terior of said conductor and also having a main valve for controlling flow through said passage, whereby when the main valves of said units are open flow of pressure fluid from exteriorly of the conductor into the interior thereof may occur, pressure-responsive means connected to each main valve and normally holding said valve closed and opening said valve when pressure is applied thereto, means for conducting the pressure fluid which is present exteriorly of the conductor to the pressure-responsive means of each main valve of the main valve units, whereby this pressure fluid is utilized to actuate the main valves, and a single control means disposed in the conducting means for controlling the application of the pressure fluid to the pressure-responsive means of the main valve units, whereby actuation of said control means results in a simultaneous operation of said main valve units.

4. A well flow apparatus as set forth in claim 3, wherein the single control means is a pilot valve which is actuated when the pressure of the fluid exteriorly of the conductor reaches a predetermined point.

5. The combination with a well liquid conductor which extends axially through a well bore, wherein a pressure lifting fluid is present in said bore exteriorly of the conductor, of a flow apparatus including, a plurality of pressure-actuated valve units carried by the conductor for controlling the admission of the lifting fluid into said conductor, and a single pressure actuated control means carried by the conductor in a position near the main valve units operatively connected with all of said valves for controlling the operation thereof, whereby when the control means is actuated the valve units are simultaneously operated to admit the lifting fluid into the conductor to raise the well liquids therein.

6. The combination as set forth in claim 5, wherein the single control means is a pilot valve which is actuated by the pressure of the lifting fluid when said fluid reaches a predetermined pressure.

7. The combination as set forth in claim 5, wherein each valve unit is pressure-actuated and also wherein the single control means controls the application of pressure to said units, whereby actuation of the control means permits pressure to be simultaneously applied to all valve units.

8. The combination as set forth in claim 5, wherein each valve unit has a pressure-responsive operating member, with means for conducting the pressure of the lifting fluid to said member to operate the same, and also wherein the single control means controls the application of pressure to the pressure-responsive means of the valve units, said control means also being responsive to the pressure of the lifting fluid, whereby when said lifting fluid pressure reaches a predetermined point, said control means is actuated to permit the application of said pressure to the pressure-responsive operating members of the valve units to simultaneously operate said units and admit a flow of the lifting fluid into the well conductor.

9. A well flow apparatus including, a well conductor which extends axially within a well bore, a pair of main valve units connected in said conductor, each unit having a flow passage estab-

lishing communication between the exterior and interior of said conductor and also having a main valve for controlling flow through said passage, whereby when the main valves of said units are open flow of pressure fluid from exteriorly of the conductor into the interior thereof may occur, each valve having operating means responsive to pressure exteriorly of the conductor for opening the valve, and a single pressure-actuated pilot valve assembly forming part of one of the main valve units and adapted to be actuated by the pressure exteriorly of the conductor, said pilot valve assembly being operatively connected to said main valve unit, a pressure line extending from the pilot valve assembly to the other main valve unit for controlling the operation of said second main valve unit, and means forming part of the pilot valve assembly and responsive to the pressure of the fluid exteriorly of the conductor for actuating the pilot valve when the pressure of said fluid reaches a predetermined point, whereby the main valve units are finally opened to admit pressure fluid into the main conductor through the main valve units upon actuation of the pilot valve assembly.

10. A well flow apparatus including, a well conductor which extends axially within a well bore, a pair of main valve units connected in said conductor, each unit having a flow passage establishing communication between the exterior and interior of said conductor and also having a main valve for controlling flow through said passage, whereby when the main valves of said units are open flow of pressure fluid from exteriorly of the conductor into the interior thereof may occur, pressure-responsive means connected to each main valve, means for conducting a pressure to said pressure responsive means which is normally holding said valve closed and which opens the valve when pressure is applied thereto, and a single control means disposed in the conducting means and actuated by the pressure of the fluid exteriorly of the conductor for controlling the application of pressure through the conducting means to the pressure-responsive means of the main valve units, whereby actuation of the single control means results in a simultaneous opening of the main valves of the main valve units to permit a flow of pressure fluid through the passages of the main valve units and into the interior of the well conductor.
